UNITED STATES PATENT OFFICE.

HENRY AUGUSTE CHALVIN, OF NEW YORK, N. Y., ASSIGNOR TO COOK & BERNHEIMER, OF SAME PLACE.

DESIGN FOR A BOTTLE.

SPECIFICATION forming part of Design No. 14,837, dated March 4, 1884.

Application filed November 5, 1883. Term of patent 14 years.

To all whom it may concern:

Be it known that I, HENRY AUGUSTE CHALVIN, a citizen of the United States, residing in the city of New York, county and State of New York, have invented and produced a new and original Design for a Bottle, of which the following is a specification, reference being had to the accompanying drawing, forming part thereof, which drawing is a perspective view 10 of a bottle containing my said design.

A is the body of the bottle, and rectangular in shape, and of plain configuration for most of its height, and B is the neck. The bottom of the neck terminates in a circular bead, C. The shoulder connecting the body with the neck has the general form of a rectangular dome, and is formed of ribs or flutings D E, which are convex on the outside, and which curve outward for a short distance, and then 20 curve inward and toward the circular bead C, upon reaching which they terminate. The ribs E are considerably narrower than the others, D, and are not put side by side; but one of the ribs D is placed between each two of 25 them. The bottoms of the ribs rest on the

bead F. The neck B forms about two-fifths of the height of the bottle, and is provided with a circular bead, G, about midway of its length. The top of the neck is provided with an annular enlargement, H.

The leading feature of my design consists of the fluted shoulder connecting the body and the neck.

What I claim as my design, and desire to secure by Letters Patent, is—

1. In a design for a bottle, the body A, surmounted by the bead F, the fluted shoulder, and the neck B, having the bead C, as described and shown.

2. In a design for a bottle, the plain body 40 portion A, surmounted by the fluted shoulder having a rectangular base and converging toward the neck, as described and shown.

In testimony whereof I affix my signature in presence of two witnesses.

HENRY AUGUSTE CHALVIN.
